UNITED STATES PATENT OFFICE.

THEODORE C. HOOK, OF PHILADELPHIA, PENNSYLVANIA.

MACHINE FOR TURNING THE EDGES OF SHEET MATERIAL.

No. 878,632.

Specification of Letters Patent.

Patented Feb. 11, 1908.

Application filed June 12, 1907. Serial No. 378,481.

To all whom it may concern:

Be it known that I, THEODORE C. HOOK, a citizen of the United States, residing at Philadelphia, in the county of Philadelphia and State of Pennsylvania, have invented certain Improvements in Machines for Turning the Edges of Sheet Material, of which the following is a specification.

This invention is a machine for turning the edges of sheet material, particularly in box covering, where it is necessary to fold the edges of the covering sheet over the edges and against the interior surfaces of boxes or parts thereof.

A chief object of my invention is to provide a simplified machine, automatic in action, by which the materials to be operated upon are positioned, the sides wiped and their ends turned, and the edges turned in with certainty and efficiency; without the necessity of carrying the wrapped box back through the machine, or of using an under plunger or plural plungers, or of having more than two stops for effecting the folding operations.

Further objects of the invention are to provide means by which the operations can be carried on rapidly, under the control of the operator, without interference with the manual manipulation of the materials to be operated upon.

In the accompanying drawings, Figure 1 is a sectional side elevation of a machine embodying my invention; Fig. 2 is a broken end elevation and section taken on the line A—A of Fig. 1; Fig. 3 is a broken top plan view; Fig. 4 is a sectional view taken on the line B—B of Fig. 1; Fig. 5 is a plan view showing in detail the relation of the tumblers and tuckers to the wrappers in process of folding; Fig. 6 is a plan view of the wrapper blank, and Fig. 7 is a broken sectional view of the head, holder and tumbler in relation to a box in process of being covered.

In the drawings, the frame 1 supports a vertical bearing 2 in which reciprocates a rod 3 carrying a head or form 4. This rod is reciprocated by means of a link 5 pivotally connected thereto, a lever 6 pivotally connected to the link and fulcrumed on the bearing 7, a link 8 pivotally connected to the lever, a lever 9 pivotally connected to the link 8 and having a fulcrum 10, a cam 11 fixed on the revoluble shaft 12 journaled in the bearings 13, and the connection 14 between the cam and the lever 9, the parts be-

ing balanced by the weight 6' on the end of the lever 6.

The box or object to be covered, with the wrapper b thereon, is carried by the head 4 upwardly between the parallel side brushes 15 fixed to the frame brackets 16, the sides of the wrapper being wiped smooth by the brushes, and brought to stationary position between the side holders 17. The holders 17 are fixed on the inner ends of the rods 18, which reciprocate in bearings 19 of the brackets 16 and have a limited movement through the couplings 20, the rods having pins 21 and springs 22 fixed to them on either side of the couplings. Tumblers 23, having the fingers 23' and 23'', are pivotally connected to rods 24 which reciprocate in bearings 25 of the brackets. The rods 24 are fixed to the couplings 20, and, by reason of the movements of the rods 18 in the couplings, the holders can be limited in movement with relation to the movements of the tumblers and tuckers. The tuckers 24*, on either side of the tumblers, are fixed to and longitudinally adjustable on the cross bar 24^b carried by the rods 24.

The holders 17 are moved inward to press and hold the sides b' of the wrapper which have been wiped by the brushes 15 against the box a carried by the head 4. In sequence therewith the tumblers 23 and the tuckers 24* are moved inward, respectively to tuck the ends b' of the wrapper's sides and to turn in the edges b'' around the edges of the box, the compression of the springs 22 and the contact of the fingers 23' with the lower portions of the holders revolving the tumblers and causing their fingers 23'' to move to the vertical position.

To reciprocate the holders, tumblers and tuckers, the couplings are pivotally connected with the links 25', the links are pivotally connected to the arms 26 fixed to the journaled spindles 27, the spindles are connected by universal joints 27' to rods 28, the rods are connected by universal joints 28' to spindle 29, the spindles 29 have fixed thereto the arms 30, the arms have pivoted thereto the rods 31, the rods are pivotally connected to the lever 32 having the fulcrum 33, and the lever is engaged by a connection 34 with the cam 35 fixed on the revoluble shaft 12.

The head 4, which has been held stationary during the operation of turning the extensions of the sides of the sheet around the

corners and over the edges of the box, rises in sequence with the withdrawal of the tumblers 23, the tuckers 24^a, and holders 17; the withdrawal of the tumblers and tuckers 5 prior to the withdrawal of the holders being effected by the actions of the springs 22 and the mechanism through which the cam 35 acts upon the couplings 20. The rising head carries the box, with the cover folded as described, between the end brushes 36 fixed to the brackets 37 which are carried by the frame. These brushes wipe the wrapper ends 18 upon the ends of the box as the latter is carried past them to its second place of rest, 10 between the holders 38. These holders press the ends of the wrapper against the ends of the box and the tumblers 39, having the fingers 39' and 39", turn the extensions of the ends of the wrapper around and within the 15 edges of the box ends.

Like the construction previously described, the holders 38 are fixed to the inner ends of the rods 40, which are adapted to reciprocate in bearings 41 of the brackets 37; 20 and the tumblers 39 are pivoted to the inner ends of the rods 42, which reciprocate in the bracket bearings 43 and have a flexible connection with the rods 40 by the couplings 43', the couplings being loose on the rods 30 and the springs 44 and the pins 45 fixed thereto. These holders and tumblers, operating as previously described, are operated by the links 46 pivotally connected to the couplings 43', the crank levers 47 fulcrumed 35 on the brackets 37 and pivotally connected to the links 46, the rods 48 pivotally connected to the crank levers 47, the levers 49 pivotally connected by the universal joints 50 with the rods 48 and having the fulcrums 40 51, the cams 52 fixed to the shaft 12 and the connections 53 between the levers 49 and the cams 52.

The shaft 12, which drives the cams, is driven by a spur gear 12' fixed thereon, a 45 pinion 54 engaging therewith, a spline shaft 55 movable through the pinion, a clutch 56 fixed to the shaft and a loose driving pulley 57 engaged to the shaft by the clutch. The clutch is engaged by a fulcrumed foot lever 58 having a crescent 59 within which revolves a grooved collar 60 fixed on the shaft 55, the clutch being automatically disengaged and the machine stopped by a coiled spring 61 placed between 55 the pulley and the clutch.

The brackets 16 are provided with slides 16' which are movable in the ways 1' of the frame and held by the set screws 62 in the position desired for properly adjusting the 60 positions of the brushes 15, the holders 17 and the tumblers 23 to the width of the box; and in the same manner the brackets 37 are provided with the slides 37' which are moved in the ways 1" of the frame and held 65 by the set screws 63 in the position desired

for adjusting the actions of the brushes 36, the holders 38 and the tumblers 39 to the length of the box to be acted upon.

The rods 8, 31, and 48 are provided with the respective turnbuckles 8', 31' and 48' for 70 adjusting their lengths to vary the movements of the head, holders and tumblers.

In the operation of the machine, it will be understood that the cams are formed and spaced so that the head is given the desired 75 step by step movement, and the box carried thereby, when it has passed the brushes 15, is stopped between the holders 17, and again between the holders 28. The cam which operates these holders and the turning devices 80 23 through the connecting mechanism is formed so as to move them inwardly, whereby the holders are caused to bear upon the sides of the box and the tuckers and tumblers to move further, by the compression of the springs 22, and turn the ends and edges of the sides. Then the tumblers and tuckers are retracted, followed by the retraction of the holders, and the head further elevates the box so that it is passed between the 90 brushes 36 to a stationary position in the range of the holders 38 and the tumblers 39. The cams 52, which operate these holders and tumblers through the connecting mechanism described, move them inwardly so 95 that the holders press the wrapper ends and the tumblers turn the extensions thereof around the edges of the box ends, after which the tumblers and holders are retracted in sequence.

Having described my invention, I claim:—

1. In a machine of the class described, a reciprocating carrying device, a holding device reciprocating transversely thereto, a turning device having a motion of reciprocation relative to the movement of said holding device and a motion of oscillation, and mechanism for connecting said parts and operating them in synchronous relation. 100

2. In a machine of the class described, a reciprocating head, a plurality of reciprocating holding devices, a plurality of turning devices each having a motion of reciprocation parallel to the motion of reciprocation of one of said holders and a motion of oscillation on 105 an axis transverse to its direction of reciprocation, means for connecting each of said turning devices with a corresponding holding device so that each turning device has a limited motion of reciprocation independent 110 of the motion of the corresponding holding device, and mechanism whereby said head, holding devices and turning devices are operated in synchronous relation.

3. In a machine of the class described, a reciprocating head, a plurality of sets of stationary brushes placed along the line of movement of said head, means for giving a step by step movement to said head, a plurality of sets of holding devices adapted to recipro- 115 120 125

cate transversely to the path of said head, a plurality of sets of turning devices adapted to reciprocate transversely to the path of said head and to oscillate on an axis transverse to said line of movement, and mechanism for operating said head, holding devices and turning devices.

4. In a machine of the class described, a reciprocating carrying device, holding devices reciprocating transversely to the path of said carrying device, and pivoted devices reciprocating relatively to said holding devices and turned by contact therewith.

5. In a machine of the class described, a reciprocating carrying device, holding devices reciprocating transversely to the path of said carrying device, pivoted devices reciprocating relatively to said holding devices and turning while said holding devices are at rest, and means for operating said parts.

6. In a machine of the class described, brushing devices, reciprocating holding devices, and oscillating turning devices reciprocating relatively to said holding devices.

25 7. In a machine of the class described, a reciprocating rod having a holding device thereon, a reciprocating rod having a turning device pivoted thereon, a flexible connection between said rods whereby one is permitted

30 a limited movement independently of the other, and means for reciprocating said rods.

8. In a machine of the class described, a set of brushes, a carrier reciprocating past said brushes, a set of holding devices reciprocating transversely to the path of said carrier, a set of oscillating turning devices reciprocating transversely to the path of said carrier, pivoted arms, means for connecting said arms with said holding and turning devices, revolute cams, and means for connecting said cams with said arms.

40 9. In a machine of the class described, a revolute shaft, a cam fixed on said shaft, a fulcrumed lever having a connection with said cam, a rod connected with said lever, a crank arm connected with said rod, a second crank arm connected with said first named crank arm, a reciprocating rod connected

with said second crank arm, and a turning device pivotally connected to said reciprocating rod.

10. In a machine of the class described, a reciprocating rod having a holding device thereon, a reciprocating rod having a turning device thereon, a flexible coupling connecting 55 said rods so that one can move independently of the other, a crank arm connected with said coupling, a second crank arm connected with said first named crank arm, a rod connected with said second crank arm, 60 a fulcrumed lever connected with said rod, and a revolute cam connected with said lever.

11. In a machine of the class described, a revolute shaft, driving mechanism, means 65 comprising a foot lever whereby said driving mechanism is engaged and disengaged with relation to said shaft, a cam fixed on said shaft, a reciprocating and oscillating turning device, a reciprocating holding device, and 70 mechanism connecting said cam with said turning and holding devices.

12. In a machine of the class described, a reciprocating tucker and an oscillating tumbler connected thereto so as to reciprocate 75 therewith.

13. In a machine of the class described, an oscillating and reciprocating turning device, and a reciprocating tucker fixed on each side of and coating with said turning device. 80

14. In a machine of the class described, a reciprocating device, a tucker fixed to said device, and a tumbler pivoted thereto.

15. In a machine of the class described, a reciprocating carrier, a holder reciprocating 85 transversely to the path of reciprocation of said carrier, and a tumbler and tucker reciprocating in paths parallel to the path of said holder.

In testimony whereof, I have hereunto set 90 my name this eighth day of June, 1907, in the presence of the subscribing witnesses.

THEODORE C. HOOK.
